CLAIM

I claim the design for electrical module for traffic lighting system, as shown and described.

DESCRIPTION

FIG. 1 is an oblique view of the electrical module for traffic lighting system showing my new design;

FIG. 2 is a left side view thereof;

FIG. 3 is a front view thereof;

FIG. 4 is a right side view thereof;

FIG. 5 is a top view thereof;

FIG. 6 is a bottom view thereof; and,

FIG. 7 is a rear view thereof.

The broken lines are included for the purpose of illustrating non-claimed subject matter and form no part of the claimed design.
